SLUG CASTING MACHINE

William L. Petersen, Springfield, N. Y., assignor
to Mergenthaler Linotype Company, a corpo-
ration of New York

Application October 31, 1936, Serial No. 108,559

20 Claims. (Cl. 199—47)

This invention relates to slug casting machines, such as Linotype machines of the general organization represented in U. S. Letters Patent to O. Mergenthaler, No. 436,532, wherein a melting pot is arranged to deliver molten metal into a slotted mold and up against a composed line of matrices to produce a type bar or slug bearing on its edge type characters corresponding to the intaglio characters of the matrices. In these machines, the molten metal is introduced into the mold by means of a spring-actuated pump piston or plunger arranged within the pot and controlled in its action by a rotary cam which, as well known, makes one complete rotation for each cycle of operation of the machine. The cam is so shaped as normally to maintain the pump plunger in a raised position out of action, but at one portion of its circumference it is formed with a depression which at the proper time permits the plunger to descend under the influence of its actuating spring to force the metal into the mold, it being understood in this connection that the distance the plunger descends or its effective stroke is largely determined by the amount of metal it displaces rather than by the depth of the depression in the cam. Since the slugs produced in the modern machines vary widely in size (both as regards length and thickness), it is evident that the effective stroke of the plunger will vary correspondingly, assuming, of course, that the metal be kept at a constant level within the pot. Thus, when casting short slugs of the thinner variety, the plunger descends only a short distance as compared with the distance it is required to travel when casting long slugs of the thicker variety. In practice it has been found that this variable condition frequently leads to the casting of defective slugs. The difficulty is that oftentimes the actual casting period is too short to permit the molten metal to congeal or solidify before the return stroke of the pump plunger, which, under such circumstances, exerts a suction effect and draws some of the metal from the mold back into the pot. The condition becomes more aggravated in the case of the larger slugs which, not only require a greater volume of metal and therefore a greater time for cooling, but which in addition necessitate a longer effective stroke of the pump plunger and correspondingly less time before it begins its return stroke.

The present invention is intended to overcome these and other objections and contemplates automatic means for delaying the return stroke of the pump plunger for a predetermined interval after the mold has been filled with molten metal

to allow additional time for the metal to solidify before the pump pressure is removed. In the present embodiment, the machine is equipped with automatic means for disengaging the main driving clutch of the machine during the effective stroke of the pump plunger so as to arrest the rotation of its controlling cam, and with automatic means actuated by the pump plunger at a later period in its effective stroke for reengaging the driving clutch to restart the rotation of its controlling cam. In this way a definite pause in the normal operation of the machine is created after the mold has been filled with molten metal, this pause corresponding to the time consumed by the plunger in moving from its mold filling position to the end of its effective stroke. In carrying out the invention the pump plunger is given a uniform effective stroke regardless of the size of the slug to be cast, the plunger being provided with a by-pass which will permit the escape of molten metal past the plunger throughout its effective stroke. Preferably, the size or area of the by-pass is variable in order to vary the time interval referred to, it being pointed out that the area of the by-pass should be greater in casting the smaller slugs (which do not require so much time to congeal or solidify) and lesser for the larger slugs (which require a longer time to congeal or solidify). In the present instance the by-pass is formed in the pump plunger and is variable by means of an adjusting device rising from the plunger above the level of the molten metal in the pot for ready accessibility.

In the accompanying drawings the invention has been shown merely in preferred form and by way of example as applied to a Linotype machine, but obviously many changes and alterations may be made therein and in its mode of adaptation without departing from its spirit. Generally speaking, it is to be understood that the invention is not limited to any specific form or embodiment, except insofar as such limitations are specified in the appended claims.

Referring to the drawings:

Fig. 1 is a side elevation, partly in section, of the casting mechanism constructed in accordance with the invention, and showing the parts in their normal position of rest;

Fig. 2 is a plan view of the pump plunger and showing the plunger rod in section;

Fig. 3 is a vertical section taken through the pump plunger and showing the variable by-pass and the adjusting device associated therewith;

Fig. 4 is a view similar to Fig. 1, but showing the plunger as it approaches the end of its ef-

fective stroke and after the machine has been stopped;

Fig. 5 is a similar view showing the pump plunger at the end of its effective stroke and after 5 restarting the machine;

Fig. 6 is an elevation of the main driving clutch of the machine with its actuating connections; and

Fig. 7 is a longitudinal section taken on the 10 line 7-7 of Fig. 4.

In Fig. 1, the parts are shown in the relative positions they occupy just prior to the commencement of the slug casting operation, the slotted mold A carried by the rotary disc A¹ being closed at the front by the composed line X, which is presented momentarily thereto by the first elevator B, and at the rear by the mouth-piece of the melting pot C, which contains a supply of type metal maintained in a molten condition 15 by means of a suitable burner or heater (not shown). The pot C is formed with a throat or passage C¹ through which the molten metal is forced into the mold by a spring-actuated plunger D, the latter being arranged to reciprocate 20 within the pot well or cylinder C² communicating with the throat C¹. The plunger D is connected by means of a rod or link D¹ to the long arm of a bell-crank lever D² having a sleeve portion D³ journaled on a fixed transverse rod D⁴ 25 of the machine frame and provided with an arm D⁵ extending laterally beneath a second lever D⁶, which is also journaled on the rod D⁴ and connected at its free end to a pull spring D⁷. The latter is anchored to the machine frame and 30 actuates the plunger D through the connections just described. The shorter arm of the bell-crank D² is provided with a roller D⁸ arranged to track upon the periphery of the usual rotary cam D⁹ fast to the main shaft of the machine. 35 As well understood, the peripheral face of the cam D⁹ is concentric throughout, except at one portion of its circumference where it is cut away or formed with a depression D¹⁰. When the machine is at rest, the roller D⁸ is in contact with 40 the concentric portion of the cam D⁹, so that the plunger D is maintained in its raised or inoperative position, as shown in Fig. 1. This condition obtains until the casting period arrives, when the cam rotating in the direction indicated brings 45 the downwardly sloping surface d of the depression D¹⁰ into engagement with the roller D⁸, which then quickly descends along such surface toward the bottom of the depression, thus permitting the spring D⁷ to depress the plunger and 50 force a charge of molten metal into the mold. In the present instance, the concentric portion of the cam D⁹ has been extended slightly, as at d², so as to overlap the sloping portion d and thus 55 correspondingly delay the depression of the plunger by the actuating spring, giving a quicker drop to the plunger than ordinarily. As the cam continues to rotate, the roller D⁸ is engaged sooner or later by the upwardly sloping surface d¹ of the depression D¹⁰, and the parts thereby 60 more gradually restored to their original condition to await the next casting operation.

The parts so far described, and their construction and mode of operation, are or may be the same as those embodied in the commercial Linotype machine and in themselves constitute no part of the present invention.

It will be understood that, during the slug casting period, the roller D⁸ will ordinarily seldom reach the bottom of the depression D¹⁰, due to 70 the fact that the plunger D will be arrested in

its descent at one level or another according to the volume of metal it displaces in effecting the cast. In the present instance, however, it is proposed to give a uniform effective stroke to the plunger regardless of the size of slug to be cast 5 so that it will always descend the same distance each time it is operated. Thus, at its lower end, the plunger is provided with an internally threaded portion D¹² formed with a vertical port or aperture D¹³ extending through the bottom 10 face of the plunger and a communicating lateral port D¹⁴ extending into the pocket D¹⁵ formed on the opposite face of the plunger for the reception of the actuating rod D¹. A valve plug D¹⁶, in the form of a long adjusting screw 15 rising above the molten metal in the pot, is screwed into the threaded portion D¹² and serves to vary the area or size of the by-pass constituted by the ports D¹³ and D¹⁴. According to this arrangement, when the pump plunger 20 D is actuated by the spring D⁷, it will descend quickly until the mold is filled with molten metal and then descend more gradually until it completes its full effective stroke, which means that the roller D⁸ will in all cases be allowed 25 to reach the bottom of the depression D¹⁰ or as close to it as may be desired. The time consumed by the plunger in moving from its mold filling position to the end of its stroke may be varied by the adjustment of the screw valve D¹⁶ 30 to suit conditions, it being desirable to prolong the period for the larger slugs and to shorten it for the smaller slugs. The variable by-pass therefore, in effect, constitutes a timing device which, as will subsequently appear, is utilized 35 in determining the pause in the normal operation of the machine during the casting period.

The main shaft G of the machine, on which the plunger controlling cam D⁹ is mounted, is driven by a large gear wheel E meshing with a 40 driving pinion E¹ of an auxiliary shaft E² which is equipped with the customary main driving clutch (see Rogers Patent No. 661,386) comprising a pulley E³ and clutch shoes E⁴ (Fig. 6). When the machine is at rest, the clutch shoes E⁴ are 45 disengaged from the pulley E³, as shown in Fig. 6, but, as is well known, when the composed line is transferred into the first elevator B, the clutch shoes E⁴ are automatically engaged with the pulley E³ to inaugurate the normal single 50 cycle of operation of the machine. Upon the completion of that normal cycle, the clutch shoes E⁴ are automatically disengaged to stop the machine. The operation of the clutch shoes E⁴ is effected by the usual clutch shifter E⁵. In 55 providing for the stopping and restarting of the machine during the casting period, these same clutch devices are utilized as will now be described.

Depending from the sleeve D³ of the pump 60 operating lever D² there is a long arm F carrying at its lower extremity an adjusting screw F¹ which is arranged to cooperate with a slide F² mounted in guideways formed in a block F³ fastened rigidly to the end of the main shaft G. 65 Consequently, as the main shaft G is rotated, the slide F² will be carried around with it. The slide F², it will be observed is formed at one end with a cam piece F⁴ arranged to cooperate with a roller F⁵ carried at the upper end of a vertical 70 lever F⁶, centrally pivoted to a fixed bracket F⁷ and carrying at its lower end a set screw F⁸ (see particularly Fig. 6) arranged to abut against one end of a rod F⁹ which is connected at its opposite end to the clutch shifter E⁵. The arrangement 75

is such that when the cam shaft G has been rotated far enough to bring the cam D⁹ to its pump releasing position, the cam piece F⁴ will engage the roller F⁵ and rock the lever F⁶ in a direction to disengage the main driving clutch, thereby stopping the operation of the machine. At this time, however, the spring D⁷ will pull the pump plunger downwardly on its effective stroke to fill the mold with molten metal, Fig. 4 showing the plunger on its way down and near the end of its stroke. In completing its effective stroke under the delaying influence of the variable by-pass formed therein, the plunger will ultimately assume the position shown in Fig. 5, and in doing so it will rock the lever F rearwardly and cause it to shift the slide F² rearwardly, such rearward movement of the slide F² moving the cam piece F⁴ clear of the roller F⁵ (as shown in Fig. 5) and allowing the main driving clutch to be reengaged under the influence of its customary spring. When this occurs, the operation of the machine will be started again, and the cam D⁹ in resuming its rotation will cause its sloping surface d¹ to engage the roller D⁸ and impart the return stroke to the pump plunger. During the return stroke of the pump plunger, the slide F² will be restored to its original position in the block F³ under the influence of a return spring F⁶. Ultimately, when the machine completes its normal cycle of operation, the parts will come to rest in the position shown in Fig. 1.

It will now be seen that the desired delay in the casting operation is brought about by first disengaging the main driving clutch to stop the machine at the beginning of the downward or the pumping stroke of the pump plunger and thereafter by reengaging the clutch to restart the machine as the plunger completes its effective stroke. It will be observed that the time interval between the stopping and the restarting of the machine is controlled by the by-pass formed in the pump plunger, this by-pass permitting the metal to escape past the plunger from the pressure chamber into the supply chamber after the mold has been filled with molten metal and allowing the plunger always to reach the end of its effective stroke. It is not necessary, of course, to vary the by-pass for each different size of slug cast, the adjustable valve plug D¹⁶ being intended merely to fix the time interval for slugs within certain ranges. For instance, in casting the smaller slugs, the by-pass may be fully opened to allow the plunger to complete its full effective stroke in the minimum time interval, whereas in casting the larger slugs, the area of the by-pass will be greatly diminished in order to increase the time interval, it being understood that in casting such larger slugs the mold filling position of the plunger will be much nearer its full stroke position. It is not essential that the by-pass in the plunger be variable because its area could be fixed with reference to the time interval required for the casting of the larger slugs, such slugs being the ones which require the delay in the casting period. By varying the by-pass, however, the time interval may be cut down for the smaller slugs which do not require the same delay in the casting period, and which without the variable by-pass would even have a greater period due to the fact that the mold filling position of the plunger is farther removed from its final effective stroke position. In practice, as above intimated, the adjustment of the by-pass will be made for different ranges of slug sizes and

will be calculated to give approximately the same time interval for the casting of all sizes.

Having thus described my invention, what I claim is:

1. In a slug casting machine, the combination of a mold, a pump plunger for filling the mold with molten metal under pressure, and automatic means for creating a pause in the normal operation of the machine after the mold has been filled with molten metal but before the machine has completed its normal cycle to allow additional time for the metal to solidify before the pump pressure is removed. 5

2. In a slug casting machine, the combination of a mold, a pump plunger for filling the mold with molten metal under pressure, and automatic means for stopping the machine during the effective stroke of the plunger and for restarting the machine at a predetermined interval after the plunger has filled the mold but before the machine has completed its normal cycle, whereby additional time is allowed for the molten metal to solidify before the plunger begins its return stroke. 15

3. In a slug casting machine, the combination of a mold, a pump plunger for filling the mold with molten metal under pressure, said plunger having a uniform effective stroke regardless of the size of the mold cavity, and automatic means for creating a pause in the normal operation of the machine after the mold has been filled with molten metal but before the machine has completed its normal cycle, said pause corresponding to the time consumed by the plunger in moving from its mold filling position to the end of its 30 effective stroke. 25

4. In a slug casting machine, the combination of a mold, a pump plunger for filling the mold with molten metal under pressure, said plunger having a uniform effective stroke regardless of the size of the mold cavity, and automatic means for stopping the machine at the beginning of and then restarting it at the end of the effective stroke of the pump plunger. 40

5. In a slug casting machine, the combination of a melting pot containing a pump well, a pump plunger arranged to reciprocate in said well, a by-pass to permit the escape of molten metal from the pressure chamber into the supply chamber of the pot during the effective stroke of the pump plunger, and automatic means for first stopping and then restarting the machine at respectively different periods in the effective stroke of the pump plunger, the time interval between the two periods being predetermined by the area 55 of the by-pass. 45

6. In a slug casting machine, the combination of a melting pot containing a pump well, a pump plunger arranged to reciprocate in said well, a by-pass formed in said plunger to permit the escape of molten metal past the same during its effective stroke, and automatic means for first stopping and then restarting the machine at respectively different periods in the effective stroke of the pump plunger, the time interval between 60 the two periods being predetermined by the area of the by-pass. 65

7. In a slug casting machine, the combination of a melting pot containing a pump well, a pump plunger arranged to reciprocate in said well, a by-pass to permit the escape of molten metal from the pressure chamber into the supply chamber of the pot during the effective stroke of the pump plunger, means for automatically stopping the machine at the beginning of the effective 70 75

- stroke of the pump plunger, and means actuated by the pump plunger at the end of its effective stroke for restarting the machine.
8. In a slug casting machine, the combination of a melting pot containing a pump well, a pump plunger arranged to reciprocate in said well, a by-pass formed in said plunger to permit the escape of molten metal past the same during its effective stroke, means for automatically stopping the machine at the beginning of the effective stroke of the pump plunger, and means actuated by the pump plunger at the end of its effective stroke for restarting the machine.
9. In a slug casting machine, the combination of a melting pot containing a pump well, a pump plunger arranged to reciprocate in said well, a by-pass to permit the escape of molten metal from the pressure chamber into the supply chamber of the pot during the effective stroke of the pump plunger, automatic means for first stopping and then restarting the machine at respectively different periods in the effective stroke of the pump plunger, the time interval between the two periods being predetermined by the area of the by-pass, and means for varying the area of the by-pass to increase or diminish the time interval between the machine stopping and restarting periods.
10. In a slug casting machine, the combination of a melting pot containing a pump well, a pump plunger arranged to reciprocate in said well, a by-pass formed in said plunger to permit the escape of molten metal past the same during its effective stroke, automatic means for first stopping and then restarting the machine at respectively different periods in the effective stroke of the pump plunger, the time interval between the two periods being predetermined by the area of the by-pass, and means for varying the area of the by-pass to increase or diminish the time interval between the machine stopping and restarting periods.
11. In a slug casting machine, the combination of a melting pot containing a pump well, a pump plunger arranged to reciprocate in said well, a by-pass to permit the escape of molten metal from the pressure chamber into the supply chamber of the pot during the effective stroke of the pump plunger, means for automatically stopping the machine at the beginning of the effective stroke of the pump plunger, means actuated by the pump plunger at the end of its effective stroke for restarting the machine, and means for varying the area of the by-pass to increase or diminish the time interval between the machine stopping and restarting periods.
12. In a slug casting machine, the combination of a melting pot containing a pump well, a pump plunger arranged to reciprocate in said well, a by-pass formed in said plunger to permit the escape of molten metal past the same during its effective stroke, means for automatically stopping the machine at the beginning of the effective stroke of the pump plunger, means actuated by the pump plunger at the end of its effective stroke for restarting the machine, and means for varying the area of the by-pass to increase or diminish the time interval between the machine stopping and restarting periods.
13. In a slug casting machine, the combination of a melting pot containing a pump well, a pump plunger arranged to reciprocate in said well, a by-pass to permit the escape of molten metal from the pressure chamber into the supply chamber of the pot during the effective stroke of the pump plunger, and an adjusting device for varying the area of the by-pass, said device being arranged within the supply chamber of the pot and rising above the level of the molten metal therein for ready accessibility.
14. In a slug casting machine, the combination of a melting pot containing a pump well, a pump plunger arranged to reciprocate in said well, a by-pass formed in said plunger to permit the escape of molten metal past the same during its effective stroke, and an adjusting device carried by the pump plunger for varying the area of the by-pass, said device being arranged within the supply chamber of the pot and rising above the level of the molten metal therein for ready accessibility.
15. In a slug casting machine equipped with a main driving clutch, the combination of a mold, a pump plunger for filling the mold with molten metal under pressure, and automatic means for disengaging the main driving clutch before and then reengaging it after the mold has been filled with molten metal to allow additional time for the molten metal to solidify before the pump pressure is removed.
16. In a slug casting machine equipped with a main driving clutch, the combination of a mold, a pump plunger for filling the mold with molten metal under pressure, and automatic means for disengaging the main driving clutch during the effective stroke of the pump plunger and for reengaging the clutch at a predetermined interval after the pump plunger has filled the mold, whereby additional time is allowed for the molten metal to solidify before the pump plunger begins its return stroke.
17. In a slug casting machine, the combination of a melting pot containing a pump well, a spring-actuated plunger arranged to reciprocate in said well, a rotary cam for controlling the active stroke of the plunger, and automatic means for stopping the rotation of the cam at the beginning and then restarting its rotation at the end of the effective stroke of the pump plunger.
18. In a slug casting machine, the combination of a melting pot containing a pump well, a spring-actuated plunger arranged to reciprocate in said well, a rotary cam for controlling the active stroke of the plunger, means for automatically stopping the rotation of the cam during the effective stroke of the pump plunger, and means actuated by the pump plunger at a later period in its effective stroke for restarting the rotation of the cam.
19. In a slug casting machine, the combination of a melting pot containing a pump well, a spring-actuated plunger arranged to reciprocate in said well, a rotary cam for controlling the active stroke of the plunger, a main shaft on which the cam is mounted, driving means for the shaft including a spring-actuated clutch, means for automatically disengaging the clutch during the effective stroke of the pump plunger, and means actuated by the pump plunger at a later period in its effective stroke for reengaging the clutch.
20. In a slug casting machine, the combination of a mold, a pump plunger for filling the mold with molten metal under pressure, and automatic means for delaying the return stroke of the pump plunger for a predetermined interval after the mold has been filled with molten metal to allow additional time for the metal to solidify before the pump pressure is removed.
